UNITED STATES PATENT OFFICE.

ABRAHAM FELLDIN, OF AUBURN, NEW YORK.

STRING STRETCHING AND TUNING DEVICE.

SPECIFICATION forming part of Letters Patent No. 408,602, dated August 6, 1889.

Application filed May 28, 1888. Serial No. 275,276. (No model.)

To all whom it may concern:

Be it known that I, ABRAHAM FELLDIN, a citizen of the United States, and a resident of Auburn, in the county of Cayuga and State 5 of New York, have invented a new and useful Improvement in String Stretching and Tuning Devices, of which the following is a specification.

My invention furnishes an improved device 10 for stretching and tuning strings, principally piano-strings, whereby the ordinary tuning-pins, which resist the tension of the strings by friction only and therefore are liable to slip and cause the strings to slacken, are entirely dispensed with, the labor of inserting 15 the strings in the agraffes and of stringing and tuning pianos is greatly facilitated, the liability to slip is completely obviated, and the needed exertion of strength on behalf of 20 the tuning-operator is reduced to a minimum.

The invention will be hereinafter fully described and specifically claimed, reference being had to the accompanying drawings, in which—

25 Figure 1 represents a front view of my improved string-tuning device in position, six of the same being shown holding six successive strings and adapted for an upright or grand piano. Fig. 2 is a side elevation of the 30 same, seen in the direction of arrow 1. Figs. 3 and 4 are side elevations of modifications of the device. Fig. 5 is a detail cross-section on the line $x-x$ of Fig. 4, looking downward. Fig. 6 is a side elevation showing a modification 35 of the agraffe and string-bridge. Fig. 7 is a cross-section on the line $y-y$ of Fig. 6, seen in direction of arrow 2.

A is the string-frame.

B are the strings fastened to the frame, as 40 at b, as usual, and thence passed over to rest upon first the lower bridge b' and then upon the upper bridge D to keep it from contact with the frame.

C is the agraffe. It is slotted vertically, as at 45 c', and notches or undercuts its vertical edges transversely at an upward inclination, thus forming grooves or notches c, in which the strings deflected from the bridge D securely lodge. The bridge D may be cast on the frame 50 A, and the agraffes, one for each note, and made, as in Figs. 6 and 7, for a three-string

instrument, screwed into the frame A behind the bridge D; but a cheaper mode, and one which always insures the relative positions of the agraffes and bridge, is to form them in one 55 piece of metal (see Figs. 1 to 4) by casting them as parallel ribs upon a continuous flat bar G, which is then secured to the frame A by screws g. The rib for the agraffe C is provided at proper intervals of space with the aforesaid 60 vertical slots c', with undercut edges forming the aforesaid grooves or notches c at one or both sides of each slot, in which notches the strings lodge, being introduced through the said slots c'; as seen in Figs. 1 and 7. 65

Instead of tuning-pins, which are liable to slip, as before stated, I provide a stretching device, which I will here call a "suspender," and which consists of a bracket-shaped piece D', (see Figs. 1 to 4,) having an arm d at about 70 a right angle to the body, and a perforated enlargement or hub d' upon the said arm for receiving a threaded rod or wire or adjusting-screw E, by which the string is stretched to the proper tension and tone. The lower part 75 of the suspender D' has a knee or leg ending with a toe d², by which it rests upon the frame A, and which has a groove for the string to rest in, and a hole through which the string is inserted and fastened in a usual manner by 80 simply bending its extreme end back upon itself, as at b², thus making it too thick for slipping through the hole. Upon the frame A is formed or cast a flange, rib, or shoulder a, upon which each screw E butts or is supported, either by its end directly, as in Figs. 2 and 4, or by a shoulder e, formed on its shank, as in Fig. 3. In the latter case the flange a is perforated to receive freely the shank of the screw E, although for the purpose of giving increased steadiness a flange a' may be so perforated to receive the screw-shank, even when the point or end of the latter bears directly on the flange a, as seen in 85 Fig. 4. As to the adjusting or tuning screw, 90 its threads work in corresponding threads, either in the hub d' of the suspender D', as in Figs. 1, 2, and 3, or in a separate hub or nut F, which fits in line with the hole in the hub d', and is provided in its side with a slot or 95 groove f, by which it grips or embraces an adjacent edge of the suspender D', and is thus 100

kept from turning. To accommodate space for the hubs d' when the suspenders D' are placed closely together side by side, as in Fig. 1, alternate suspenders are shorter than the others, so that their hubs do not come in the same row, but the hubs of the shorter suspenders are covered by the bodies of the larger, and the hubs of these latter are covered by the screws E of the shorter suspenders, as shown in Fig. 1; hence two flanges or shoulders a at different elevations are used, when the suspenders are supported on them by the points of the screws E , as in Figs. 1, 2, and 4. It is evident that by these suspenders no slack of the strings can possibly occur by slipping, as is frequently the case when ordinary tuning-pins are used.

Having thus described my invention, I claim as new and desire to secure by Letters Patent—

1. The combination, in a string stretching and tuning device, of a string-frame, as A, having the string-holding studs b , bridges b' D, agraffe C, and shoulder or shoulders a , for the stretching-screws, the suspender-yokes and stretching-screws, said yokes bridging said shoulders and having toes of the string ends bearing at one side of the shoulders on the surface of the string-frame, and heads for the adjusting-screws on the other side of the

shoulders and in line with the surface of the string-frame or thereabout, substantially as described.

2. The combination, in a string-stretching device, of a string-frame, as A, having the string-holding studs b , bridges b' D, agraffe C, and upper and lower shoulders a , for the stretching-screws, the suspender-yokes and stretching-screws, said yokes bridging said shoulders and having toes of the string ends bearing at one side of the shoulders on the surface of the string-frame, and heads for the adjusting-screws on the other side of the shoulders gaged for the bearing of the adjusting-screws on the upper and lower shoulders alternately, substantially as described. 45

3. The combination of an agraffe C, having vertical slots c' , provided with side notches c , with a bridge D, said bridge and agraffe being both rigid upon a common bar G, securable to the string-frame. 50

In testimony that I claim the foregoing as my invention I have signed my name, in presence of two witnesses, this 23d day of May, 1888.

ABRAHAM FELLDIN.
